UNITED STATES PATENT OFFICE.

ORVILLE D. COTTON, OF DAYTON, OHIO, ASSIGNOR TO HERBERT M. COTTON, OF DAYTON, OHIO.

MECHANICALLY-OPERATED FURNACE.

1,233,554.

Specification of Letters Patent. Patented July 17, 1917.

Application filed May 4, 1916. Serial No. 95,335.

To all whom it may concern:

Be it known that I, ORVILLE D. COTTON, a citizen of the United States, residing at Dayton, in the county of Montgomery and 5 State of Ohio, have invented a new and useful Improvement in Mechanically-Operated Furnaces, of which the following is a specification.

This invention relates to a new and useful 10 improvement in mechanically-operated furnaces.

The principal object of my invention is the strengthening and preserving of the ribbed plate upon which the furnace fire arch 15 rests and for which it forms the base. Experience has demonstrated that the ribbed plate is likely to warp or crack and allow portions of the plate to sag, thus to a greater or less degree shortening the life of the arch 20 and also interfering with the regular discharge of the coal from the magazines onto the grates. By the use of this method of strengthening and supporting the arch plate, I provide against these defects.

25 The preferred form of embodiment of my invention is illustrated in the accompanying drawings, of which Figure 1 is a front elevational view of my improvement as applied to the type of furnace shown in 30 United States Letters Patent No. 1,018,649, granted February 27th, 1912. Fig. 2 is a rear view thereof. And Fig. 3 is a sectional view taken on the line A—A of Fig. 1, showing in addition thereto parts of the fire arch 35 and stoking mechanism.

Throughout the specification and drawings, similar reference characters denote corresponding parts.

In a detailed description of the preferred 40 form of embodiment of my invention as applied to a mechanically-operated furnace of the type disclosed in the above mentioned patent, the numeral 1 designates the magazine bed plate and 2 the feed opening 45 through which the coal passes from the magazines to the grates. Supported by the bed plate 1 is an arch plate 3 provided with a series of ribs 4, the upper portion 5 of said arch plate as shown, forming a part of the 50 magazine.

For the purpose of strengthening and preserving the arch plate 3, there is provided a form of construction which will now be described. Above the magazine bed plate 1 the arch plate 3 has an inclined portion provided in its lower side with a longitudinal groove 5^a which receives a metal bar 6. An angle iron 7 or other metallic member, rests upon the ribs 4 of the plate 3, and is connected to the bar 6 by means of bolts 8 or other fastening means. Therefore, the bar 6 and angle member 7 coöperate to strengthen and prevent the warping or sagging of the arch plate 3. In Fig. 3, the numeral 9 designates a section of the arch, showing how it is supported by the ribbed plate 3 and angle member 7 secured to the latter; while the numeral 10 designates the fuel magazine and the numeral 11 a section of the grate of the furnace.

Having described my invention, I claim:

1. In a mechanically-operated furnace, a coal magazine, an arch plate having an inclined portion, a countersunk element on the lower side of said inclined portion, a coöperative member on the upper side thereof, said countersunk element and coöperative member each extending substantially the full length of said arch plate, and means for connecting said member and countersunk element at intervals whereby they coöperate to prevent the warping and sagging of said plate.

2. In a mechanically-operated furnace, a coal magazine, an arch plate having an inclined portion provided in its lower side with a longitudinal groove, a bar in said groove, a coöperative angle piece substantially coextensive in length with said arch plate, on the upper side of the inclined portion of the latter, and bolts for drawing said angle piece and bar tightly against said plate whereby they coöperate to prevent the warping and sagging of the latter.

3. In a mechanically-operated furnace, a magazine bed plate, an arch plate forming the top of a clear and free feed opening above said bed plate, a portion of said arch plate above the magazine bed plate being inclined, a countersunk element on the lower

side of said inclined portion, a coöperative member on the upper side thereof, said countersunk element and coöperative member each extending substantially the full length of said arch plate, and means extending, at intervals, from said coöperative member to the opening, to connect said member and countersunk element whereby they

coöperate to prevent the warping and sagging of said arch plate.

In testimony whereof, I have hereunto set my hand this 1st day of May, 1916.

ORVILLE D. COTTON.
